UNITED STATES PATENT OFFICE.

FRANCIS A. PETER, OF DEIBERTSVILLE, PENNSYLVANIA.

DESIGN FOR A CELLAR-GRADE.

SPECIFICATION forming part of Design No. 16,740, dated June 15, 1886.

Application filed February 24, 1886. Serial No. 193,090. Term of patent 7 years.

To all whom it may concern:

Be it known that I, FRANCIS A. PETER, a citizen of the United States, residing at Deibertsville, in the township of Washington, county of Lehigh, and State of Pennsylvania, have invented and produced a new and original Design for Cellar-Grates, of which the following is a specification, reference being had to the accompanying drawings, forming part ¹⁵ thereof.

Figure 1 is a front view of my newly-designed cellar-grate; Fig. 2, a side or end sectional view as if the frame of grate was cut through upright at indication-lines I, shown in ¹⁵ Fig. 1. Fig. 3 shows a side sectional view of grate and frame as when cut through at indication-lines H in Fig. 1.

These three views are deemed necessary to fully illustrate my design. In these the front ²⁰ view of the frame and swing-grate together show in appearance a wood-work finish, and as carved.

The leading features of my design consist of ornamentation in intaglio of substantially

the design shown in Fig. 1, excepting the main ²⁵ columns L and fillets B are raised on the main face of grate-frame A.

A is the main face of the grate; B, the raised fillet with the ornamentation in intaglio, as shown; C, the square block with roseate. D ³⁰ and e show the main frame in the swing-grate. X shows the ornamental parts in the grate. K is the back part of the frame. L shows the columns, which are ornamented as shown; I and H, indication-lines. ³⁵

I claim—

1. The design for a cellar-grate, consisting of frame A, herein shown and described, the same representing ornamental carved-in and raised figures, having the shape and ornamentation shown. ⁴⁰

2. The design for a cellar-grate, the same consisting of frame A and grate D, shaped and ornamented as shown. ⁴⁵

FRANCIS A. PETER.
